ARTHUR F. WHITE, OF FULLERTON, AND FRANK W. JORDAN, OF LOS ANGELES, CALIFORNIA, ASSIGNEES, BY MESNE ASSIGNMENTS, TO JORDAN & TAYLOR, INC., OF LOS ANGELES, CALIFORNIA, A CORPORATION OF CALIFORNIA

VALVE CONSTRUCTION FOR GAS LIFT PUMPS

Application filed September 5, 1928. Serial No. 304,052.

Our invention relates to the well-pumping art, and more particularly to a novel valve for use on a gas-lift well pump.

One type of gas-lift pump particularly advantageous in pumping oil wells is described and claimed in an application of Arthur F. White, filed August 6, 1928, Serial No. 297,665, entitled Method and apparatus for pumping wells. That application 10 discloses a chamber at least partially submerged in the liquid in the lower part of a well. A delivery tube extends into this chamber to a point near the lower end thereof and forms a portion of a discharge passage 15 communicating with the surface of the ground. Compressed gas is supplied to the upper end of the chamber through a suitable pressure-operated valve which opens when the pressure on one side exceeds the pressure 20 in the chamber by a predetermined amount.

It is an object of our invention to provide a novel form of pressure-operated valve useful, for example, in a gas-lift pumping mechanism.

25 We have found it advantageous to utilize a valve which will pop open upon the occurrence of a small difference of pressure between the compressed gas passage and the interior of the pumping chamber, and which 30 will remain open as long as any compressed gas is passing through the valve.

It is an object of our invention to provide a valve structure which will pop open upon the occurrence of a small difference in pressure, and which will remain open during the time that a compressed gas is passing therethrough.

35 A further object of our invention is to provide a valve member which is pivoted about a given axis; one end of this valve member controlling the operation of a primary intake valve structure and the other end of this valve member controlling a secondary output valve structure.

40 A further object of our invention is to provide a valve member carrying a floating valve head adapted to engage a valve seat and thereby control the passage of the gas 45 through a passage.

Further objects and advantages of our invention will be made evident hereinafter.

Referring to the drawings, in which we illustrate a preferred form of our invention,

55 Fig. 1 is a utility view illustrating our invention as applied to one type of gas pump.

Fig. 2 is a vertical sectional view of the valve of our invention.

60 Fig. 3 is a sectional view taken on the line 3—3 of Fig. 2.

Fig. 4 is a sectional view taken on the line 4—4 of Fig. 2.

65 Fig. 5 is a sectional view taken on the line 5—5 of Fig. 2 showing the valve in a closed position.

70 Fig. 6 is a face view of one end of the valve member of our invention taken in the direction of arrow 6—6 of Fig. 2.

75 Referring particularly to Fig. 1, in which one type of gas-lift pump is illustrated, the numeral 8 represents a well in which a casing 9 has been set, this casing being perforated at its lower end to allow well-fluid to enter 10 therein, this well-fluid rising to a liquid-level indicated by the numeral 10.

80 A head 11 is formed on the upper end of the casing 9 and a primary tubing 13 extends through this head and downward into the well, and supports at its lower end a gas-lift pumping mechanism 14 incorporating our invention. The upper end of the primary tubing 13 is closed by a head 16 through 85 which a secondary tubing 17 passes. The gas-lift pumping mechanism 14 has a head 18 threadedly received by the lower end of the primary tubing 13, this head having a bore 19 providing a seat 20 against which a plug member 21 fits in fluid-tight relationship, this plug member being threadedly received by the lower end of the secondary tubing 17. A bore 23 through the plug member 21 communicates with the interior 90 of the secondary tubing and also with a bore 24 formed axially in the head 18. A similar bore 25 is formed upward in the head 18 and to one side of the axis thereof, the bores 24 and 25 being in communication with each other.

95 100

A shell 28 is threadedly received by the lower end of the head 18 and cooperates therewith to form a pumping chamber 29. A delivery tube 30 is threadedly received by the bore 25 and extends downward in one side of the chamber 29 to a point near the lower end thereof. This chamber is quite long and should be at least partially submerged in the liquid in the casing 9. This liquid has access to the interior of the pumping chamber through a liquid-intake valve 33, this valve preventing any liquid from leaving the pumping chamber 29 through the opening closed thereby.

15 A passage 35 is formed through the head 18 and communicates at one end with the annular space between the primary and secondary tubings 13 and 17 and at the other end with a pocket 36 formed in the lower face of the head 18. This pocket is threaded and adapted to receive a plug 37 forming a part of a valve body 38 which in turn is a part of the pressure-operated valve mechanism 40 of our invention. This valve body 25 is substantially round and extends into the pumping chamber 29 on the opposite side of the axis thereof from the delivery tube 30.

An inlet passage 42 is formed in the valve body 38 so as to communicate with the passage 35 when the plug 37 is threaded in the pocket 36. The lower end of the passage 42 communicates with a pressure chamber 45 which in turn communicates with the chamber 29 through a longitudinal channel 46 formed along the valve body 38.

The pressure chamber 45 is formed as indicated in Fig. 2 and is cylindrical in cross-section when viewed in the direction indicated by the arrow 6—6. A seat 47 is formed at the junction of the intake passage 42 and the pressure chamber 45, this seat being contacted by a primary valve head 48. The head 48 and the seat 47 cooperate to form the primary valve structure 50 of our invention.

50 As best illustrated in Figs. 2 and 3, the primary valve head 48 is carried in one end of a valve member 52 extending in the longitudinal channel 46 and pivoted on an axis 52 A—A formed by a pin 53, this pin extending through the portions of the valve body on either side of the channel 46, and also through the valve member 52, so that this valve member may be regulated on this pin.

55 On the upper end of the valve member 52 is formed a head 55 which is circular in shape and adapted to extend a short distance into the pressure chamber 45, the innermost position being determined when the primary valve head 48 contacts the seat 47, which position is shown in full lines on Fig. 2. The valve member is held in this position by a compression spring 56 which extends into channels 57 and 58 formed respectively in

the lower ends of the valve body 38 and valve member 52.

As best illustrated in Figs. 2 and 3, the primary valve head 48 is designed to float relative to the upper end of the valve member 52, this floating action taking place because of the fact that this valve head is slightly smaller than the opening 59 in which it fits.

The head is retained in position by means of an annular channel 60 which retains an enlargement 61 formed on the rear of the head 48. The head is inserted in place through a threaded opening 62 which is normally closed by a threaded plug 63, this plug being held in position by a pin 64 passing through a channel 65 thereof and through the valve member 52, as best illustrated in Fig. 3. The plug 63 is screwed into the opening 62 a sufficient distance so that the head 48 may not be tightly clamped in place but may move in the opening 59 a short distance, which is preferably in the neighborhood of several thousandths of an inch. A pressure-relief passage 67 communicates between the channel 65 and the annular channel 60 so that this channel will be at the same pressure as the pumping chamber 29.

As best illustrated in Fig. 1, a vent passage 68 is formed through the head 18 and communicates with the interior of the casing 9. The lower end of this vent passage communicates with an annular channel 69 formed in the upper end of the valve body 38 and lying adjacent to the lower face of the head 18 when the plug 37 is screwed into the pocket 36. The annular channel 69 in turn communicates with an outlet passage 70 extending downward through the valve body 38 and communicating with the pump chamber 29 through the longitudinal channel 46.

A seat 71 is defined at the point where the outlet passage 70 opens on the longitudinal channel 46. A secondary valve head 72 is adapted to engage the seat 71 when the valve member 52 is in its dotted line position indicated by the numeral 73 of Fig. 2, the secondary valve head 72 and the seat 71 cooperating to form a secondary valve structure 74 which controls the communication between the chamber 29 and the vent passage 68 through the outlet passage 70. As best illustrated in Figs. 2 and 5, the secondary valve head 72 is loosely retained in an opening 76 formed in the valve member 52 on the opposite side of the axis A—A from the opening 59 in which the primary valve head 48 is placed.

The head 72 has an enlargement 77 which may slide in an annular channel 78, the outer end of which is threaded to receive a plug 79. A compression spring 80 is compressed between the plug 79 and the head 72 and serves the purpose of normally holding the enlargement 77 against a ledge 81 which separates the annular channel 78

from the opening 76. The amount of the compression of this spring may be regulated by turning the plug 79, this plug being normally retained in correct position by a pin 82 extending through the valve member 52 and through a channel 183 formed across the plug 79. A pressure-relief passage 85 communicates between the annular channel 78 and the pumping chamber 29 and is for a purpose analogous to the pressure-relief channel 67. The spring 80 is compressed, as shown in Fig. 5, when the valve member 52 assumes its position indicated by dotted lines 73, thus insuring a tight closure of the secondary valve structure 74.

The operation of our invention is as follows:

With the valve member 52 in the position shown in full lines in Fig. 2, the upper portion of the chamber 29 is vented to the exterior of the pumping mechanism 14, thus allowing liquid to rise in the pumping chamber 29 to a level corresponding to the liquid-level 10 of the well. The compressed gas is at this time forced through a pipe 86 which communicates with the annular space between the primary and secondary tubings 13 and 17. The flow of this compressed gas is determined by a suitable intermittent valve 87, the particular form of which does not form a part of this invention. This compressed gas passes downward between the annular space in the tubing and through the passages 35 and 42 and builds up a pressure against the primary valve head 48. When this pressure becomes sufficiently greater than the pressure in the pumping chamber 29, the spring 56 will be compressed and the primary valve structure 50 will open slightly, thus allowing the compressed gas to enter the compression chamber 45. As the pressure in this chamber builds up, the valve member 52 is thrown into its dotted line position 73, thus compressing the spring 56. At this time the compressed gas enters the upper end of the pumping chamber 29, and forces the liquid therein upward through the delivery tube 30 and through the secondary tube 17 to the surface of the ground. A check valve 82 in the lower end of the delivery tube 30 prevents any return flow of the liquid.

It should be clear that as soon as the primary valve structure 50 pops open, and the valve member 52 assumes its dotted line position 73, the inrushing gas will impinge against an impact face 83 formed on the head 55. This impinging of the inrushing gas holds the valve member 52 in its dotted line position against the action of the spring 56 so that there will be no tendency of the primary valve structure 50 to close when the pressure in the pumping chamber 29 starts to build up as the liquid is being forced upward through the delivery tube 30. An an-

nular channel 84 is formed in the impact face 83, as best shown in Figs. 2 and 6, this channel increasing the force on the upper end of the valve member due to the inrushing compressed gas being discharged from the inlet passage 42.

It should be clear that when the primary valve structure 50 starts to open the secondary valve structure 74 is closed due to the valve member 52 pivoting on the pin 53. Any further movement of the valve member 52 after the valve structure 74 is closed merely compresses the spring 80. This closing of the secondary valve structure prevents any of the liquid or gas in the pumping chamber 29 from passing through the outlet passage 70 and the vent passage 68.

When at least a portion of the liquid in the pumping chamber 29 has been discharged upward through the delivery tube 30, the intermittent valve 87 closes, thus cutting off the supply of compressed gas to the annular space between the tubing 13 and 17. This stops the flow of compressed gas through the inlet passage 42 and consequently removes the force holding the valve member 52 in its dotted line position.

The spring 56 thus acts to move the valve member into its full line position, thus venting the upper end of the chamber 29 to the exterior of the pumping mechanism 14 through the outlet passage 70 and the vent passage 68. At this time the primary valve structure 50 is closed and remains so until a new supply of compressed gas is forced downward from the surface of the ground, at which time this sequence of operations is repeated.

The particular construction of the valve heads 48 and 72 with respect to the valve member 52 is an important part of our invention inasmuch as the floating action of these valve heads allows them to firmly engage the seats 47 and 71 respectively. If it were not for this floating action, it would be necessary to very accurately machine the ends of the valve heads so that they will alternately come into surface contact with their respective seats when the valve member 52 is moved.

The pressure chamber 45 is also an important part of our invention. We have found that a valve that is pressure-operated directly against the action of the spring will tend to chatter when the pressure in the chamber 29 builds up, due to the fact that a predetermined difference of pressure must be maintained between the inlet passage 42 and the chamber 29 before such a valve will open and stay open.

We have further found that the particular shape of valve illustrated is very effective in performing the desired function, this valve taking up a relatively small amount of room. So, also, the placing of the delivery tube 30

to one side of the chamber 29 is important to our invention inasmuch as such a position allows adequate room for any valve that may be inserted in the chamber.

5 It should be understood that our invention is not limited to the particular use shown, but is also applicable to any installation where it is desirable to have a pressure-operated valve which in a single movement uncovers a fluid-intake passage and closes a fluid-outlet passage. Our invention should thus not be limited other than by the subject-matter defined, and the nomenclature used, in the appended claims.

15 We claim as our invention:

1. In combination, a cylindrical valve body including a pressure-fluid passage, a pressure chamber, a valve seat located in said pressure chamber in communication with said pressure-fluid passage, an outlet passage, a valve seat at the entrance of said outlet passage, a longitudinal channel, a spring channel; a valve member pivotally mounted in said longitudinal channel and including a circular head forming an impact face positioned at one end of said valve member and arranged to project into said valve body pressure chamber, and a spring channel positioned adjacent said valve body spring channel; a primary valve loosely mounted in said valve member circular head whereby said primary valve will close said pressure-fluid inlet passage; a secondary valve loosely and resiliently mounted in said valve member and arranged to close said outlet passage valve seat when said primary valve opens; and a spring member arranged in said valve body and valve member spring channels to resiliently hold said valve member in position to close said primary valve.

2. In combination, a valve body including a pressure-fluid passage, a pressure chamber, a valve seat located in said pressure chamber in communication with said pressure-fluid passage, an outlet passage, a valve seat at the entrance of said outlet passage, and a longitudinal channel; a valve-carrying member pivotally mounted in said longitudinal channel and including a circular head positioned at one end and arranged to project into said valve body pressure chamber; a primary valve loosely mounted in said valve-carrying member circular head and arranged to contact said pressure-fluid valve seat; a secondary valve loosely and resiliently mounted in said valve-carrying member and arranged to contact said outlet passage valve seat when said primary valve opens; a spring member arranged to resiliently hold said valve member in position to close said primary valve whereby the pressure of the pressure-fluid forces said primary valve to open and the velocity and pressure of the pressure-fluid acting upon said valve-carrying member circular head holds said valve open until said

velocity and pressure fall below a predetermined value.

3. In combination, a valve body including a pressure-fluid passage, a pressure chamber, a valve seat located in said pressure chamber in communication with said pressure-fluid passage, an outlet passage, a valve seat at the entrance of said outlet passage; a valve-carrying member pivotally mounted on said valve body and including a circular head positioned to project into said valve body pressure chamber; a primary valve suitably mounted on said valve-carrying member; a secondary valve loosely and resiliently mounted in said valve-carrying member and arranged to contact said outlet passage valve seat when said primary valve opens; a spring member arranged to resiliently hold said valve member in position to close said primary valve.

4. In combination, a valve body including a pressure-fluid passage, a pressure chamber, a valve seat located in said pressure chamber in communication with said pressure-fluid passage, an outlet passage, a valve seat at the entrance of said outlet passage; a valve-carrying member pivotally mounted on said valve body and including a circular head having a reactance groove positioned to be acted upon by the pressure-fluid; a primary valve suitably mounted on said valve-carrying member; a secondary valve loosely and resiliently mounted in said valve-carrying member and arranged to contact said outlet passage valve seat; and a spring member arranged to resiliently hold said valve member in position to close said primary valve.

In testimony whereof, we have hereunto set our hands at Los Angeles, California, this 31st day of August, 1928.

ARTHUR F. WHITE.
